UNITED STATES PATENT OFFICE.

DANIEL W. DAVIS, OF BEAUMONT, TEXAS.

MOSQUITO NET.

Application filed November 3, 1925. Serial No. 66,614.

My present invention relates generally to mosquito nets, and more particularly to mosquito nets as designed for personal wear in order to protect the head, face, and neck 5 from mosquitoes in these localities where these insects abound to such an extent as to make them extremely painful if not dangerous.

Among its various objects my invention 10 proposes a netting shield which when entirely closed, can be worn without discomfort, and which provides for partial opening to expose the eyes and mouth, which will permit of easy, comfortable use of the arms, 15 and at the same time fully protect even in the partly open position all portions of the head, face, and neck, except those parts purposely exposed in certain positions.

Other and further objects of my invention 20 together with the resulting advantages thereof, will be readily apparent from the following description, reference being had to the accompanying drawings which illustrate my present invention, and in which:

25 Figure 1 is a perspective view showing my improved shield in practical use with the parts in fully closed position.

Figure 2 is a similar view showing the eye covering raised in open position,

30 Figure 3 is a central vertical section through the shield in the position shown in Figure 1.

Figure 4 is a perspective view showing the eye covering raised and the face portion in 35 lower position exposing the mouth.

Referring now to these figures, my invention is a mosquito net or shield for personal wear including a head frame of light, simple and adjustable construction and a hood of 40 flexible foraminous material which depends from the head frame, and is controlled and adjusted to some extent by the latter, together with an eye covering, the front portion of the hood being so constructed as to present 45 a front or facial portion whose upper edge normally depends slightly below the eyes in use constituting a sight space which is covered by the eye covering with the latter in its lower active position and is uncovered 50 when the eye covering or flap is turned or folded upwardly into engagement with the head frame. As will be hereinafter shown, the facial portion of the hood is so arranged and constructed that while normally held 55 with its upper edge slightly below the level of the eyes in use it may be drawn down-

wardly so as to expose the greater portion of the face and especially the nose and mouth, and has means in its lower stretched position, the eye covering having means to hold the same in lower active position independent of the particular position of the facial portion of the hood.

Accordingly the head frame includes an upper head ring 10 consisting of a flexible 65 member whose ends are tied as at 11 so as to render the ring, which passes through the upper looped ends of a series of radial tapes 12, readily adjustable. The head frame also includes a lower circular head 70 band 13 to which the lower ends of the several radial tapes 12 are connected. This head band which is formed of flexible material has secured therein around its front portion a forehead covering strip 14, and is 75 provided along its rear portion over the ends of said strip 14 with an elastic cord and the like 15, whose ends are tied as at 16 at the central rear portion of the head band whereby the latter may be readily adjustable as 80 to its head size to snugly surround the head and firmly hold the strip 14 across the forehead. By drawing the ring 10 inwardly it is obvious that the band 13 may be elevated, and by letting out the ring 10 the band may 85 be correspondingly dropped.

The hood includes front and rear sections 17 and 18, joined at their meeting side edges by a sheath 19 having therein an elastic cord 20, the upper end of the sheaths being secured to the central side portions of the head band 13 and the lower ends thereof being secured to the upper central portion of elastic members 21 which define arm holes and to the lower portions of which similar body embracing members 22 are connected. The lower edges of the front and rear portions 17 and 18 of the hood are attached to the members 21 and 22, and the elastic side connections thus permit the head and the body engaging portions of the hood to be worn without discomfort and at the same time, in such manner that the hood is stretched well away from the head below 95 the head encircling band 13 and maintained well away from the neck, ears, and the lower portion of the face under normal conditions. 100

Along its upper edge the rear portion 18 of the hood is securely fastened to the head encircling band 13, and at its side portions the upper edge of the front portion 17 of the hood is likewise secured to band 13, al- 110

though the remaining portion of the upper edge of the front section 17 is left free to depend below the forehead strip 14 sufficient-
ly to form a slit or space ample for all pur-
poses of ordinary vision. Along the free
portion of its upper edge the front section
17 has incorporated in said edge an elastic
band or cord 23 whose ends are attached to
the side portions of the head encircling band
13, this strip extending in the normal posi-
tion of the parts across the bridge of the
nose immediately below the eyes. Along its
upper front portion adjacent to the elastic
band or cord 23, the facial portion of the
hood is left full in order that the elastic
band or cord 23 may be stretched downwardly
to the position shown in Figure 4, where
it exposes the central portion of the face
including the nose and mouth as shown, and
where it may be held for convenience in eat-
ing or for other purposes necessitating ex-
posure of the mouth, by means of an elastic
loop 24 whose ends are attached to the elastic
cord or band 23 at spaced points upon op-
posite sides of the center of the latter. In
the normal position of the parts as shown in
Figure 1, this chin-engaging loop 24 is in-
active and simply hangs free upon the out-
side of the hood.

Upon the inside of the hood a flexible
elastic cord 25 adapted to be passed under
the chin is connected at its upper ends by
cords 26 and 27 to the elastic cord 23 and to
the central side portions of the head band,
and this flexible elastic strip or cord 25 serves
to hold the upper front edge of the hood
below the eyes in the normal position as
shown in Figure 1.

Secured along the front portion of the
head encircling band 13 is one edge of an
eye covering 28 adapted to be folded down-
wardly to the position shown in Figure 1
in order to cover the space between the fore-
head strip 14 and the elastic cord 23 along
the free edge of the facial portion of the
hood, and adapted also to be folded upward-
ly to an inactive position against the head
frame, as shown in Figure 4. This eye
covering 28 which is formed of a material
similar to that of the hood, has at its free
edge an attaching loop 29 which in the lower
effective position of the eye covering is
adapted to extend beneath the nose of the
wearer as indicated in Figure 1, and which,
in the upper inactive position of the eye
covering, is adapted for engagement with the
hook 30 secured to the front radial strap 12
of the head frame.

It is thus obvious that since the support of
the eye covering 28 is not dependent in any
way upon the facial portion of the hood, this
eye covering may be lowered to partly cover
the face when the facial portion of the hood
is stretched downwardly to the position
shown in Figure 4, thus protecting the eyes,

nose, and portions of the cheeks, while the
mouth is exposed as when eating in a locality
where the mosquitoes are especially bad.

It will also be noted from the foregoing
that with the parts properly adjusted no
portion of the hood is drawn tightly against
any portion of the neck or face of the wearer
except across the nose, and for this reason,
the facial portion of the hood is provided
with a nose pad 31 adjacent to its upper
central portion which contacts with the nose
in the normal position of the facial portion
of the hood with either the eye covering
lowered, as in Figure 1, or raised, as in Fig-
ure 2. Furthermore, inasmuch as the eye
covering may, as previously described, be
lowered and held in effective position with
the facial portion of the hood stretched
downwardly below the mouth, and inasmuch
as in this position the eye covering itself
will be held snugly across or against the
nose, it is preferable that the eye covering
have a nose pad 32 centrally thereof, as par-
ticularly seen in Figures 2 and 4.

My improved mosquito net or shield is
such that it may be readily and easily
assumed and removed, and is so constructed
as to be strong and durable in use as well as
effective and efficient for the intended pur-
poses. Moreover, my invention presents a
netting or shield for personal wear which
may be worn without discomfort, which per-
mits of ready turning and twisting of the
head, which admits of easy exposure of the
mouth when necessary, and one in which the
necessary adjustments may be readily and
quickly made, and when once made for a
particular person, will remain throughout
the natural life of the shield.

Obviously my improved shield being of
flexible construction throughout, is readily
foldable in disuse to occupy a minimum of
space either upon the person or within a
baggage carrier.

I claim:-

1. A mosquito netting or shield for per-
sonal wear including a head frame, compris-
ing a head band, a head ring, and a series
of radial tapes connecting the head band and
head ring, both said band and said ring be-
ing adjustable for the purposes set forth.

2. A mosquito netting or shield for per-
sonal wear including a head frame, a hood
depending from the head frame and free at
the upper edge of its front portion from the
head frame, an elastic member in the said
free edge of the hood normally supporting
the said edge in slightly spaced relation be-
low the head frame in use, and a chin engag-
ing loop connected to the upper front por-
tion of the hood for engagement with the
chin when the elastic upper free edge is
drawn downwardly substantially below its
normal position to expose the mouth in use.

3. A mosquito netting or shield for per-

sonal wear including a head frame, a hood depending from the head frame and free at the upper edge of its front portion from the head frame, an elastic member in the said free edge of the hood normally supporting the said edge in slightly spaced relation below the head frame in use, and an elastic freely depending within the hood for extension beneath the chin in use, said elastic having connection at its upper edge with the sides of the head frame and the side portions of the upper free edge of the hood whereby to hold the said upper free edge of the hood snugly against the face below the eyes in use.

4. A mosquito netting or shield for personal wear including a head frame, a hood

depending from the head frame and having a free upper elastic edge at the front of the head frame adapted to normally hang slightly below the head frame whereby to form an eye opening, and an eye covering flap attached to the front of the head frame and foldable downwardly and upwardly respectively to and from effective position covering the said eye opening, and a nose engaging loop carried by the free edge of said eye covering flap, said head frame having a member engageable by said loop in the upper inactive position of the eye covering flap.

DANIEL W. DAVIS.
